(57) **CLAIM**

The ornamental design for a hair dryer, as shown and described.

DESCRIPTION

FIG. 1 is a perspective view of a hair dryer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a hair dryer shown in a first configuration of use;

FIG. 10 is a perspective view of the hair dryer shown in a second configuration of use;

FIG. 11 is a perspective view of the hair dryer shown in a third configuration of use; and,

FIG. 12 is an enlarged view of portion 12 shown in FIG. 8. The broken lines in the drawings depict portions of the hair dryer that form no part of the claimed design.
